UNITED STATES PATENT OFFICE

GEORGE E. SWINEHART, OF BUFFALO, NEW YORK, ASSIGNOR, BY MESNE ASSIGNMENTS, TO AMERICAN ORE RECLAMATION COMPANY, OF CHICAGO, ILLINOIS, A CORPORATION OF ILLINOIS

SINTERING MACHINE

Application filed March 18, 1930. Serial No. 436,924.

- This invention relates to sintering machines, and more particularly to machines for sintering ores, flue dust and other materials containing combustible ingredients.
- 5 In sintering machines the material to be sintered is deposited upon a grate and is ignited, after which combustion is propagated throughout the mass by causing passage of an air current through the same. In the
- 10 Dwight and Lloyd type of sintering machine, for which my invention is particularly adapted, a plurality of pallets, forming a train, are moved along an endless track. The pallets of the upper run of the track travel beneath the feed hopper from which the material is discharged onto the grate sections of the pallets, after which the pallets pass beneath an ignition device which serves to
- 15 ignite the material and, during the continued travel of the pallets along the upper run of the track they pass above a succession of wind boxes by means of which a down draft is produced through the material so that combustion is propagated downwardly through
- 20 the mass. At the discharge or delivery end of the machine, the sintered material is discharged from the pallet. In general, materials to be sintered contain fine particles, commonly designated as fines, and relatively large or coarse particles, commonly designated as aggregates. It is the present practice to deposit the material upon the grate of the
- 25 pallet with the fines and aggregates intermixed indiscriminately. As a result, the fines are often disposed directly upon the upper face of the grate section and act to clog or stop up to an appreciable extent, the openings or perforations through the grate. This
- 30 is objectionable as seriously interfering with flow of air and products of combustion through the grate section, with the result that the combustion of the material is retarded and the output of the machine is correspondingly curtailed.
- 35 I have found that it is possible to separate the fines and aggregates of the material to be sintered, by gravity, during operation of the machine and in such manner as to dispose the aggregates directly upon the upper
- 40 face of the grate section, the fines being disposed upon the aggregates.
- The aggregates being relatively large or coarse provide a lower loose and porous grate layer which will not clog the grate, and this lower layer serves to support the upper layer of fines out of contact with the grate surface. This is highly advantageous as eliminating clogging or stoppage of the grate sections, thus promoting more rapid combustion of the material and greatly increasing the output of the machine. One of the main objects of my invention is to provide simple and efficient means whereby the material, as it is delivered to the grate sections, is separated by gravity into aggregates and fines, the aggregates being deposited directly upon the grate sections and the fines being deposited upon the lower layer of aggregates thus formed.
- 45 A further object of my invention is to provide means of the character described which can readily be applied to a sintering machine of the continuous type without in any way interfering with the operation of such machine. Another object is to provide means for separating the material into fines and aggregates and for delivering the aggregates to the grate sections in advance of the fines and during travel of the pallets. Further objects and advantages of my invention will appear from the detailed description.
- 50 In the drawings:
- Figure 1 is a vertical sectional view through the feed hopper and associated parts of a continuously operating sintering machine, showing my invention as applied thereto, parts being shown in elevation, this section being taken substantially on line 1—1 of Figure 2;
- 55 Figure 2 is a transverse vertical sectional view through the feed hopper and associated parts, taken substantially on line 2—2 of Figure 1;
- 60 Figure 3 is a section taken substantially on line 3—3 of Figure 2;
- 65 Figure 4 is a section through a layer of material, such as is deposited upon the grate sections in accordance with present practice, the fines and aggregates being intermixed indiscriminately;
- 70 Figure 5 is a section through a layer of ma-

terial such as is deposited upon the grate sections in accordance with my invention, this material being separated into fines and aggregates, the aggregates forming a lower layer 5 and the fines forming an upper layer superposed upon said lower layer.

I have illustrated my invention as applied, by way of example, to a sintering machine of the Dwight and Lloyd type. Such 10 machines are well known in the art and need not be illustrated nor described in detail.

The machine comprises a main frame 1 to which rails 2 are suitably secured, these rails forming tracks at the upper run of the machine. The tracks thus formed receive rollers 3 of pallets 4 which are suitably propelled along the upper run of the track. The pallets are elevated from the lower run of the track in a known manner, as by means of 15 sprocket wheels, and are propelled along the upper run of the track, forming a train the pallets of which are in contact with each other. Each of the pallets 4 carries a grate 5 of any suitable or preferred type, this grate being provided with perforations or openings to permit of ready passage therethrough of air and products of combustion during travel 20 of the pallets over the wind boxes.

A hopper frame 6, of suitable type, is 30 mounted upon the main frame 1 in a suitable manner and adjacent the feed end of the machine. A feed hopper 7 is suitably supported in frame 6 and extends downwardly to within a short distance of the pallets 4. This hopper 35 comprises front wall 8, rear wall 9, and downwardly converging side walls 10 provided at their lower ends with extensions or wings 11 disposed to project downwardly a short distance into the pallets 4 so as to direct the material into the same.

A gate plate 12 is disposed adjacent the front face of wall 8 of the hopper. This plate is secured to two angle strips 13 which are secured at their ends to Z-shaped strips 14, the 45 forward flanges of which operate between guide strips 15 and angle bars 16 to which these strips are secured, the angle bars being secured to uprights 17. Sleeves 18 are secured to the strips 14, these sleeves being inferiorly threaded for reception of adjusting screws 19. The screws 19 are rotatably mounted through bearing brackets 20 suitably mounted upon an upper cross angle bar 21 of the hopper frame. A bevel gear 22 is 50 secured upon the upper end of each of the screws 19 and meshes with a bevel gear 23 secured upon a shaft 24 rotatably mounted in the brackets 20. A hand wheel 25 is secured upon shaft 24 for operating the latter. 55 By rotating the hand wheel 25 in proper direction the plate 12 can be raised and lowered as desired.

The material to be sintered is delivered to the hopper 7 by swinging spout 26, which 60 swings transversely of the hopper on an axis

extending fore and aft thereof, this spout being operated in a known manner. It is the present practice to provide the hopper 7 with a fixed plate which is inclined downwardly and forwardly of the hopper, the material being delivered from the spout onto the upper face of this plate, which discharges the material downwardly and forwardly against the lower portion of front wall 8 of the hopper. 70

The material thus discharged collects at the front wall of the hopper in a pile upon the traveling grate sections, the fines and aggregates being indiscriminately intermixed. As the grate sections pass beneath plate 12, this plate serves to scrape off or remove the material to an extent depending upon the adjustment of the plate, thus forming upon the grate sections of the pallet a layer of material of substantially uniform depth. In this layer of material the fines and aggregates are intermixed indiscriminately, so that an appreciable portion of the fines is disposed at the bottom of the layer, as in Figure 4, directly upon the upper face of the grate sections. These fines stop up or clog the openings of the grate sections, during the sintering operation, and materially reduce the rate of combustion and the output of the machine, as above pointed out. 80

I have found that the above noted objections to the present practice can be avoided by depositing the material upon the grate sections in such manner as to cause separation, by gravity, of the larger and heavier particles or aggregates from the fines, and disposing the aggregates thus separated directly upon the grate sections so as to provide a lower loose and porous layer of aggregates. This result can be accomplished by disposing the material in a pile or ridge so inclined that the larger and heavier particles or aggregates will roll by gravity to the bottom of the pile so as to be disposed directly upon the surface of the grate sections, while the smaller and lighter particles, or fines 100 remain at the upper portion of the pile. 105

The angle of repose for materials to be sintered varies with the character of the material, and the moisture content thereof. To obtain the most efficient results, it is desirable to vary the position of the top of the pile or ridge of material formed, in such manner that the largest amount of coarse particles or aggregates in a given sintering mixture will roll to the bottom of the bed or layer to be sintered so as to be disposed directly upon the grate surface, thus protecting the grate and increasing the porosity of the bed. I find that this result can readily be accomplished by providing a baffle plate or deflector arranged so that it can be adjusted with facility and in angular relation to the front wall of the feed hopper. This plate may be considered as constituting the effective front wall of the feed hopper which, 110 115 120 125 130

in the broader aspects of my invention, is not essential under certain conditions.

In the embodiment of my invention illustrated, I provide a deflector in the form of a 5 baffle plate 27 which is hinged at its upper edge, at 28, to the upper edge of front wall 8 of the hopper 7. The plate 27 is provided, adjacent the lower end and each side there- 10 i, with an elongated slot 29 which receives 15 an adjusting rod 30 upon the forward end of which is secured an abutment member 31 having a rounded surface contacting the forward face of plate 27.

Rods 30 pass through a channel bar 32 15 which extends transversely of rear wall 9 of the hopper, and has threaded engagement through collar 33 suitably secured to the bar 32. A hand wheel 34 is suitably secured upon the rearward end of each of the rods 20 30 for rotating it and adjusting the plate 27 toward or away from front wall 8 of the hopper. The spout 26 is disposed to direct the material delivered therefrom onto the rearward face of plate 27, this material flowing 25 downwardly along the plate so as to form a pile at the lower end thereof. By properly adjusting the angular relation of plate 27 relative to front wall 8 of the hopper, that is by properly adjusting the plate 27 on its 30 hinge axis, the inclination of the rearward face of the ridge or pile of material formed at the lower end of the plate can be varied, within limits, to suit the particular material being treated. The adjustment of the plate 35 27 is such that the larger particles or aggregates of the material will readily roll down the pile onto the upper face of the grate section, the finer particles or fines remaining at the upper portion of the pile. As a result 40 of this adjustment of the plate, the material to be sintered is separated, by gravity, into aggregates and fines, the aggregates being deposited upon the grate sections in advance of the fines so as to form a loose and 45 porous lower layer or thickness of material upon which the fines are deposited to provide an upper layer or thickness superposed upon this lower layer of aggregates.

The lower layer of aggregates is designated 50 35, the upper layer of fines being designated 36. Referring more particularly to Figures 4 and 5, it will be noted that in Figure 4, which may be considered as representative of the present practice, an appreciable 55 quantity of fines is disposed at the bottom layer of material, which is objectionable since these fines, being directly upon the grate surfaces, clog and stop the openings of the grate to an objectionable degree. In Figure 5, 60 which may be considered as illustrative of my invention, the material is disposed in two distinct layers, the lower layer 35 of course particles or aggregates being disposed upon the grate surfaces to provide a loose and porous 65 layer which facilitates ready passage

therethrough of air and products of combustion while avoiding stoppage of the openings of the grate section. The upper layer 36 of fines is superposed upon the lower layer 35 of aggregates and this lower layer serves to prevent entry of the fines into the grate openings, so as to avoid stoppage thereof. I thus avoid, by my invention, the objections to the present practice in sintering machines, above 70 pointed out, while providing simple and highly efficient means whereby the material to be sintered is separated, by gravity, during the continuous operation of the machine into fines and aggregates, and the aggregates and fines are deposited upon the grate section in two layers, the aggregates forming the lower layer and the fines the upper layer. 75

My invention can be applied to continuous sintering machines of known type without necessitating any material changes in the machine and has the great advantage of preventing clogging of the grate sections, thus materially increasing the rate of combustion and the output of the machine. The particular embodiment of my invention illustrated is by way of example only, and changes in construction and arrangement of parts may be resorted to without departing from the field and scope of the same, and I intend to include all such variations, as fall 80 within the scope of the appended claims, in this application in which the preferred form only of my invention is disclosed. 85

What I claim is:—

1. In combination in a sintering machine, 100 a plate, a grate structure traveling beneath the plate, the plate being inclined downwardly and contra to the direction of travel of the grate structure, and means for delivering material to be sintered to the plate remote from the lower end thereof and in a freely flowing stream against the rear inclined face of the plate.

2. In combination in a sintering machine, 105 a plate, a grate structure traveling beneath the plate, the plate being inclined downwardly and contra to the direction of travel of the grate structure, and a spout disposed to deliver material to be sintered to the plate remote from the lower end thereof and in a freely flowing stream against the rear inclined face of the plate.

3. In combination in a sintering machine, 110 a plate, a flat grate structure traveling beneath the plate, the plate being inclined downwardly and contra to the direction of travel of the grate structure and said flat grate structure extending rearwardly beyond the plane of the plate a sufficient distance to permit of materials delivered from the plate accumulating in a ridge upon the grate structure and in rear of the plane of the plate, and means for delivering material to be sintered 115 to the plate remote from the lower end there- 120

- of and in a freely flowing stream against the rear inclined face of the plate.
4. In combination in a sintering machine, a traveling flat grate structure, a plate above the grate structure and inclined downwardly and contra to the direction of travel of the grate structure, and means for delivering material to be sintered to the grate structure in a stream flowing freely downwardly along the rear inclined face of the plate from a point remote from the lower end of said plate and at a rate commensurate with the rate of travel of the grate structure, said flat grate structure extending rearwardly beyond the plane of the plate a considerable distance sufficient to permit of the delivered material accumulating in a ridge upon the grate structure and in rear of the plane of said plate.
- 20 In witness whereof, I hereunto subscribe my name this 14th day of March, 1930.
